UNITED STATES PATENT OFFICE.

EUGENE A. FAIRBANKS, OF HOLLAND, MICHIGAN.

FIREARM.

Application filed June 19, 1922. Serial No. 569,438.

To all whom it may concern:

Be it known that I, EUGENE A. FAIRBANKS, a citizen of the United States, residing at Holland, in the county of Ottawa and State of Michigan, have invented certain new and useful Improvements in Firearms of which the following is a specification.

My invention relates to improvements in fire arms, and more particularly in small fire arms, as pistols, small fowling pieces, and the like, and its objects are: first, to provide a means whereby the hammers and the triggers may be so securely locked in cocked position that it will be impossible to fire the arm until the locking element has been disengaged from both the hammer and the trigger; second, to provide a means whereby all the internal working parts of the gun lock and its accessories may be mounted upon the trigger plate; third, to provide a means whereby a pistol grip fire arm may be readily converted into a "stock" gun, and vice versa.

I attain these objects by the mechanism and arrangement of parts shown in the accompanying drawing, in which Fig. 1 is an elevation of a pistol grip fire arm with the side plate removed to disclose the several elements necessary for bringing about the several objects hereinbefore mentioned. Fig. 2 is a like view with the gun barrel "broken down" as for the purpose of discharging the cartridge shells or reloading the barrels of the gun. Fig. 3 shows the trigger plate removed from the gun stock, in elevation, to show the manner of locking the hammers and triggers in place. Fig. 4 is a plan of the same with the hammers removed. Fig. 5 is a like view with the hammers in place. Fig. 6 is a front elevation of the same showing offsets upon the hammers for contacting the firing pins upon a double barreled fire arm with one barrel directly above the other. Fig. 7 is a plan and an elevation of the locking bolts and their actuating elements. Fig. 8 is a plan of the locking device with the sustaining element shown in section to disclose the means for holding said element safely upon the surface of the trigger plate. Fig. 9 is a plan of the bar that forces the hammers into operative position when the gun is "broken down." Fig. 10 is a plan of the cartridge shell extractor. Fig. 11 is a back elevation of the barrels showing the openings therein for locking the barrels in

operative position upon the stock or grip. Fig. 12 is an enlarged side elevation of the trigger plate illustrating how the hammers and triggers of a double barrel gun may be locked in position. Fig. 13 is a side elevation of a fire arm of the pistol class with a gun stock attached. Fig. 14 is a back end elevation of a pistol grip showing the several holes therein for connecting a gun stock therewith. Fig. 15 is a side elevation of the metal extension by means of which the gun stock is secured to the pistol grip.

Similar reference characters indicate similar parts throughout the several views.

In the construction of this gun the barrels 1 and 2 are mounted with one immediately above the other, and are pivotally mounted upon the front end of the stock plate 3 as at 4, so the barrels may be readily thrown from the position shown in Fig. 1 into the position shown in Fig. 2, and vice versa. These barrels are locked into normal position upon the stock by means of locking pins or bars 13, which said bars are held in locking position by a rod 14 having a cross head 80 designed to engage the ends of the bars 13, as indicated in Figs. 1, 2 and 7, said rod 14 being pivotally connected with a second rod 17, as at p, see Fig. 7, and is forced forwardly by means of a spring, as indicated at 16 in Figs. 1 and 2, said spring being located upon the rod 14 between the supporting element q in the gun stock, through which the rod 17 passes, as at 18, in Fig. 1, and the collar r on the rod 14. 90 The rod 17 is provided with a slot s, (see Fig. 7) through which the stem 19' on the thumb slide 19, passes, so that if the slide 19 is drawn backwardly toward the back surface of the pistol grip the rod 17, and with it the rod 14 will be drawn backwardly and will draw the bolts 13 out of the holes j in the gun barrel, and thus release, or unlock the gun barrels so they may be thrown into the position shown in Fig. 2.

The hammers 5 and 5' are pivotally mounted upon the supporting post 6', on the trigger plate 32, by means of the pivot pin 6, so they may be readily made to oscillate thereon, backwardly and forwardly. The 105 hammers are forced forwardly against the firing pins 35, by means of a rod, or rods 30 which are pivotally connected with the hammers as at b, and pass through an opening in the standard 23, and are actuated to 110

throw the hammers forcibly against the firing pins by a coiled spring 31, mounted upon each actuating rod 30. When it is desired to remove, or to return a cartridge from, 5 or into a barrel of the gun the locking bolts 13 are withdrawn as hereinbefore explained, and the barrels carried downwardly into the position indicated in Fig. 2, when the incline 11, pressing against the inclined end of the 10 cocking slide 10, forces the end 12 of said slide against the inclined surface *t* of the hammer and forces the hammer back into the position indicated in Fig. 2, against the tension of the spring or springs 31. This 15 slide is made to reciprocate in the opening 34 between the walls 33 on the trigger plate 32, so that its action must be direct and unvaried.

When the hammer or hammers have been 20 thrown backwardly into the position shown in Fig. 2 they may be firmly locked in place by means of the rod 25 which is made to slide freely through an opening in the standard 23, and is provided with a head having 25 an upper arm 26 and a lower arm 27 forming an opening into which the catch 7 on the hammer may pass, as indicated in Figs. 1, 2, 3 and 12, and thereby lock the hammer, or hammers firmly in position. At the same 30 time the arm 27 will rest directly upon the projecting end *v* of the triggers 8 and render it impossible to move the triggers, thus affording a double safeguard against the premature discharge of a cartridge in the gun. 35 The rod 25 is forced forwardly into position to engage the catch 7 on the hammer, by means of a properly adjusted spring, as indicated at 28. The rod 25 is drawn backwardly to disengage the arms 26 and 27 40 from the catch 7 by means of the bell crank lever 21—22, which is pivotally mounted into the upper end of the standard 23, as at of the arm 21 of said lever being made to press upon the incline 24 on the stem 19' of the slide 19, and the arm 22 of said lever being 45 made to engage the slot or notch *g* in the back end of the rod 25. When it is desired to lock the hammers in place in "cocked" position, the slide 19 is drawn backwardly 50 until the arm 21 of the actuating lever rests upon the extreme point of the incline 24 and the spring 28 will force the rod 25 into position to engage the catch 7, as hereinbefore explained, and the end of the trigger or triggers, so the trigger or triggers 8 cannot be 55 made to become disengaged from the notch *u* in the hammer or hammers. If it is desired to free the hammers so the cartridges may be exploded it is simply necessary to move the slide 19 forwardly until the end of the arm 21 of the actuating bell crank lever is raised sufficiently to cause it to rest upon the ledge 20 on the stem 19', when the bolt 25 will be drawn backwardly against the tension of the spring 28, and the hammers and

triggers will be free to operate. That is, the operator may draw upon either trigger, and the corresponding hammer will be released and thrown forwardly by the spring 31 with sufficient force to cause the corresponding firing pin to indent the percussion cap in the cartridge and explode the powder therein. 70

36, in Figs. 2 and 11, represents the shell extractor, the lip *i* being designed to extract 75 the shell from the upper barrel, and the part *i'* being designed to extract the shell from the lower barrel.

To prevent the locking lever 25 from being drawn upwardly by the force of the spring against the hammer or hammers a pin *h* is secured in the front end of said shaft and is made to project forwardly therefrom and pass into the hole *h'* in the backwardly extending part 6" of the hammer supporting post 6'. 80

I prefer that the hammer actuating slide 10 be provided with an actuating spring, as indicated at *w*, that will force the slide into normal position when the barrels 1 and 2 are returned into normal position, as this averts the danger of too sudden movement of the slide when the hammer is released from the trigger and is forced suddenly forward by the spring 31. J—J, in Fig. 11 represents holes in the back end of the barrel part of the gun into which the locking pins 13 are forced to lock the said barrels in place upon the end of the grip of the gun. 90

e represents a downwardly extending arm integral with the trigger plate 32 that forms a part of the grip 37, and *d* represents the trigger guard in common use upon all guns of the character herein set forth. 9 represents the spring that actuates the trigger to force it back of the notch *u* in the hammer when the hammer is drawn backwardly into "cocked" position, as indicated in Figs. 2 and 12. 100

To meet the requirements of users who may desire a more steady means of holding the gun than can be achieved with the use of the pistol grip 37, I have provided for connecting a gun stock extension upon the grip, as shown at 38 in Fig. 13. This stock extension is provided with a metal grip piece, 39, which is provided with a "thumb" screw 40 that is designed to screw into the hole *k* in the pistol grip, and draw the stock 38 firmly in place thereon, and, also, with one or more pins, as 41, that are designed to pass into the holes *n*—*n* and prevent the stock from revolving upon the screw 40 and becoming displaced, or being thrown out of proper alignment with the grip. 115

a—*a'* represents offsets upon the hammers 5 and 5' in position to properly contact the firing pins 13, as desired. *C* represents the pivotal support of the triggers and *f*—*f* are 120

holes through which pins may be passed to secure the trigger plate to the breech block 3. *m* is an opening in the stock plate 39 for the head of the screw 40.

5 With the hammers 5, the triggers 8, and their several adjunctive elements mounted upon the trigger plate 32 it is a simple matter to assemble, or to dissemel these parts without the use of a tool of any kind, after 10 the trigger plate has been removed from the gun stock.

With my construction the thumb slide acts in three capacities, as follows: first, with it in the position indicated by its solid lines in Fig. 1 it forces the locking pins 13 into the holes in the breech of the gun-barrels and locks the barrels firmly in place. At the same time the locking device, 26—27, is disconnected from both the hammers and the 15 triggers and the gun may be fired as desired. Second, when the thumb slide is carried backwardly into the position indicated by its dotted lines in Fig. 1 the barrels will still remain locked in place and, at the same time, 20 the hammer lock will be allowed to move forwardly into position to rest upon the end of the triggers and to engage the end 7 of the hammers and lock said triggers and hammers so firmly in cocked position as to render it impossible to draw the trigger or triggers and fire the gun until the thumb slide has been moved forwardly into its most 25 forward position, indicated by its solid lines in Fig. 1. Third, when the thumb slide is moved backwardly into the position indicated in Fig. 2, the pins 13 will be drawn entirely clear of the barrels and the barrels 30 may be "broken down" into the position indicated in Fig. 2 for removing the empty shells, and for reloading the gun, as desired.

The slot S in the rod 17 should be made considerably longer than the width of the arm 19' of the thumb slide 19 so the thumb 45 slide may be moved far enough backwardly to allow the locking bolt 26—27 to lock the hammer and the trigger in place before the pins 13 are drawn out of engagement with the barrels 1, but short enough so the pins 50 will be drawn out of such engagement with the further movement of the slide.

Having thus fully described my invention, what I claim as new in the art, is:

1. In combination with the barrel, the

breech and the hammers and the hammer 55 actuating mechanism of a breech loading fire arm, a trigger pivotally mounted in position to hold the hammer in "cocked" position, a locking bolt having an upper short arm and a longer lower arm forming a slot 60 between them, said bolt mounted upon the trigger plate in position to be made to slide longitudinally so the catch on the hammer will be made to enter the slot in the locking bolt and the end of the trigger body will be 65 secured under the longer arm of the locking bolt head, a spring for forcing the locking bolt into contact with the catch on the head and over the end of the trigger body, a thumb slide mounted upon the breech of the gun 70 and having a downwardly extending body thereon, an incline and a ledge formed upon the lower end of said body, a bell crank lever pivotally mounted so one arm of said lever will contact with the incline and ledge, and the other end will engage the end of the locking bolt in such a manner that when the thumb slide is slid forwardly the lever 75 will draw the bolt out of contact with the hammer and the trigger, and when the thumb slide is slid backwardly the end of the lever will slide downwardly upon the incline and allow the locking bar to be forced into contact with the catch on the hammer and the end of the trigger body to 80 lock the hammer in "cocked" position.

2. In combination with the elements covered in claim 1, means whereby the throwing of the barrels into break down position will automatically move the hammers into 85 cocked position.

3. In combination with the elements covered in claim 1, the locking elements so arranged that a one half backward movement of the locking slide will leave the barrels 90 locked in normal position and will lock the hammer and the trigger in cocked position.

4. In combination with the elements covered in claim 1, offsets extending inwardly from the inner edges of the hammers in position to extend by each other and actuate the firing pins to discharge an upper and a lower barrel in direct vertical alinement without danger of interference between the hammers or the said offsets.

Signed at Holland, Mich., June 2, 1922.

EUGENE A. FAIRBANKS.
